CONTROL FOR REFRIGERATING APPARATUS

Leslie B. M. Buchanan, Springfield, Mass., assignor to Westinghouse Electric & Manufacturing Company, East Pittsburgh, Pa., a corporation of Pennsylvania

Application August 18, 1937, Serial No. 159,658

10 Claims. (Cl. 62—4)

My invention relates to refrigerating apparatus and has for an object to provide an improved control therefor.

5 A further object of my invention is to control the operation of a refrigerating machine in response to the temperatures of different zones being cooled.

10 A further object of the invention is to limit the maximum temperature of a cooling element of a refrigerating machine and the minimum temperature of the media cooled thereby.

15 A still further object of the invention is to provide an improved thermostatic control for a refrigerator that responds to temperature conditions in a plurality of remotely disposed regions.

20 These and other objects are effected by my invention as will be apparent from the following description and claims taken in connection with the accompanying drawing, forming a part of this application, in which:

Fig. 1 is a diagrammatic view of a refrigerator mechanism controlled in accordance with my invention; and

25 Fig. 2 is a sectional view taken along the line II—II of a detail shown in Fig. 1.

I have chosen to show my invention applied to a conventional single evaporator refrigerator of the domestic type but it is to be understood that other forms of refrigerating apparatus may be controlled equally well including two temperature machines wherein a plurality of evaporators are employed and operating at different temperatures. The present invention defines an improvement over the control shown and claimed in my copending application, Serial No. 159,657, filed August 18, 1937, and assigned to the assignee of the present application. In this copending application, I have disclosed a control of the general type shown in the present application applied to various forms of refrigerators including a form wherein two different temperatures are maintained in different chambers.

45 The control disclosed in the present application operates in a similar manner to the control of the aforementioned copending application but is an improvement thereover in that the minimum temperature maintained in the higher temperature zone may be in excess of the maximum temperature of the low temperature zone. In both the present and the copending applications, operation of the compressor is initiated in response to a predetermined high temperature of one zone being cooled and is terminated in re-

sponse to a predetermined low temperature of another zone.

Reference will now be had to the drawing wherein I have disclosed a cabinet structure 10 formed of insulating walls and defining a chamber 11 for articles to be refrigerated. An evaporator 12 of any suitable type is disposed in heat transfer relation with the air in the chamber 11 and may include means for supporting trays 13 in which media to be congealed or maintained at sub-freezing temperatures may be disposed.

Circulation of refrigerant through the evaporator 12 is effected by a refrigerant condensing unit generally shown at 14 and preferably including a compressor 15 driven by an electric motor 16, and a condenser 17, the latter being cooled in any well known manner such as, for example, by means of a fan 18. Refrigerant vaporized in the evaporator 12 at relatively low pressure and temperature by heat abstracted from the air in the chamber 11 and the media in the trays 13 is withdrawn from the evaporator 12 through a suction conduit 19 by the compressor 15. The withdrawn vapor is compressed to a relatively high pressure by the compressor 15 and is delivered through a conduit 21 to the condenser 17 wherein it is cooled and condensed. Liquid refrigerant passes from the condenser 17 to the evaporator 12 through a conduit 22 having a suitable expansion device, such as, for example, a conventional capillary tube 23 connected thereto. The pressure of the refrigerant is reduced as it passes through the tube 23 so that vaporization at relatively low temperature may be effected in the evaporator 12. The system described heretofore operates on the well known compressor-condenser-expander cycle but it will be understood that other forms of refrigerating systems may be employed and controlled in accordance with the invention.

In practicing my invention, I provide a control mechanism generally shown at 25 for initiating and terminating operation of the condensing unit 14 in accordance with temperature conditions in different zones of the chamber 11. 45 The mechanism 25 includes an expansible bellows 26 having a tube 27 connected thereto and communicating with a plurality of reservoirs 28 and 29 for containing a volatile fluid. The reservoirs 28 and 29 may be of any suitable construction 50 but, as shown, are defined by bulbs communicating with the tube 27.

The charge of fluid in the system defined by the bellows 26, the tube 27, and the reservoirs 28 and 29 is such that liquid is present in one of 55

the reservoirs 28 or 29 while the remaining reservoir, the tube 27 and the bellows 26 contain gas. The pressure in a thermal responsive system charged in this manner will always correspond to the lowest temperature to which any part of the system is subjected. The reason for this operation is because the fluid collects in the region of lowest temperature and, therefore, the pressure of vaporization is determined by the temperature of said low temperature region. It will be apparent, therefore, that normally the reservoir 28 being in heat transfer relation with the evaporator 12 or in a zone of low temperature is the lowest temperature portion of the thermal responsive system and contains the liquid. Accordingly, expansion of the bellows is responsive to the temperature of the reservoir 28 and the evaporator 12. Should the temperature of the reservoir 28 be heated to a value in excess of the temperature of the reservoir 29 which is normally higher in temperature than the reservoir 28, the fluid vaporized in the reservoir 28 would condense in the reservoir 29 and, therefore, movement of the bellows 26 would be in accordance with the temperature of the reservoir 29. As the reservoir 29 responds to the temperature of the air in the chamber 11, movement of the bellows would be in accordance with the temperature of the air in the chamber 11 or higher temperature zone.

In order that the control of the movement of the bellows may be transferred from the low temperature reservoir 28 to the reservoir 29, sufficient heat is imparted to the reservoir 28 to elevate its temperature above that of the reservoir 29. This may be accomplished in any suitable manner but, preferably, I employ the heat of the condensed liquid for this purpose. Accordingly, a portion of the conduit 22 is disposed in heat transfer relation with the evaporator 12 and the reservoir 28, as shown at 31. During operation of the compressor 15, the circulated refrigerant heats the reservoir 28 so that control is effected by the reservoir 29 and during inactive periods of the compressor when circulation of refrigerant and heating of the reservoir 28 is substantially terminated, the reservoir 28 becomes the controlling element. Further reference to the transfer of control of the expansion of the bellows 26 will be made hereinafter.

The construction of the thermostat 25 will now be described in detail. A frame member 32 provides a support for the various elements of the thermostat mechanism 25 and has the bellows 26 secured thereto in any suitable manner. Movement of the bellows 26 is imparted to a lever 33 that swings about a fixed pivot 34. A spring 35 biases the bellows 26 in opposition to the pressure therein and bears against an adjusting screw, shown at 36. Upward and downward movement of the lever 33 is limited by respective stops 37 and 38 which are adjustable as shown.

A second lever 39 may be carried by the pivot 34 and is actuated by the lever 33 through a lost motion connection preferably including a spring 41 secured to the lever 33 and engaging the lever 39 as best shown in Fig. 2. The spring is moved by the bellows 26 and the lever 33 and effects movement of the lever 39 through frictional engagement therewith. Upward and downward movement of the lever 39 is limited by stops 42 and 43, respectively, which may be made adjustable as shown. The angular movement of the lever 33 is greater than the angular movement of the lever 39 so that the lost motion connection defined by

the spring 41 and lever 39 permits overtravel of the lever 33 with respect to the lever 39 during a movement of these members and subsequent to the engagement of the lever 39 with one of its stops 42 and 43.

A switch mechanism generally indicated at 44 is actuated by the lever 39 and includes a stationary contact shown diagrammatically at 45 and a movable contact 46, the latter being carried by a movable support 47 pivoted at 48 to the frame. An over-center spring 49 connects the lever 39 to the support 47 and effects a snap-action of the latter in a switch closing and opening direction as the center of the spring passes the center of the pivot 48. Downward movement of the contact support 47 is limited by a stop 51. The switch mechanism 44 which I have shown defines one form that may be employed, but it will be understood that any suitable form of switch mechanism may be used.

The compressor motor 16 is energized from a suitable power source represented by line conductors L₁—L₂ under control of the switch 44. Closing and opening of the switch initiates and terminates operation of the motor 16 and the compressor 15.

Operation

As shown in the drawing, the switch 44 is open as the temperature of the evaporator 12 is below the value at which operation of the compressor is started. Circulation of condensed refrigerant in heat transfer relation with the thermal element or reservoir 28 is not effected at this time so that this reservoir is colder than the reservoir 29 and, therefore, controls expansion of the bellows 26. The pressure in the bellows 26 is relatively low so that the lever 33 engages the stop 38.

In the description which follows, it will be assumed that the compressor is started in response to a predetermined maximum evaporator temperature of 30° F. and stopped when the temperature of the air in the space 11 has been depressed to 42° F. The maximum temperature of the air in the space 11 at the time of starting the compressor and the minimum temperature of the evaporator 12 at the time of stopping the compressor will vary, depending upon their respective heat loads. In the description which follows, it will be assumed that the temperature of the air in the space 11 increases to 45° F. during the inactive periods of the compressor and that the minimum temperature of the evaporator 12 is 24° F.

The stop 38 is adjusted to limit downward movement of the lever 33 and contraction of the bellows when the pressure in the bellows corresponds to a temperature somewhat lower than 30° F., say 29° F. The other stop 37 limits upward movement of the lever 33 and expansion of the bellows 26 when the pressure corresponds to a temperature somewhat in excess of 42° F., such as 43° F. The amount of movement of the lever 39 permitted by the stops 42 and 43 is just sufficient to permit operation of the switch 44 and is of less angular extent than the amount of movement of the lever 33.

As operation of the compressor has just been terminated by the opening of the switch 44, the temperature of the air in the chamber 11 is 42° F. and the temperature of the evaporator is 24° F. Heating of the reservoir 28 by the warm condensed refrigerant is terminated so that the reservoir 28 becomes colder than the reservoir 29 and, therefore, becomes the controlling factor for determining pressure in the bellows 26. As the

temperature of the evaporator 12 and of the air in the space 11 increase due to the heat load thereon, the pressure within the bellows progressively increases. Expansion of the bellows is prevented by the bias of the spring 35 until the pressure therein obtains a value corresponding to 29° F.

As the temperature of the evaporator increases above 29° F., the pressure within the bellows 26 is sufficient to start upward movement of the lever 33. Upward movement of the lever 33 is also effected, being frictionally engaged with the spring 41. When the temperature of the evaporator is increased to a value of 30° F., the lever 33 will have been moved sufficiently to effect engagement of the contacts 45 and 46. The motor 16 is therefore energized and circulation of refrigerant by the compressor 15 is started. Heating of the reservoir 28 is initiated so that control of the pressure in the bellows is transferred to the reservoir 29. As the reservoir 29 is subjected to a relatively high temperature of air in the space 11, the pressure in the bellows rapidly increases. At this time, the temperature of the air in the space 11 is relatively high, for example, 45° F.

The rapid increase in pressure in the bellows 26 effects upward movement of the lever 33 until it engages the stop 37. Upward movement of the lever 33 is prevented, however, by the stop 42 and, therefore, overtravel of the lever 33 with respect to the lever 39 is permitted by the lost motion connection defined by the spring 41 of the lever 39. Operation of the compressor 15 effects a reduction in temperature of the evaporator 12 and the air within the space 11. The pressure within the bellows 26 is progressively decreased but contraction of the bellows is not effected at temperatures above 43° F. as the bias of the spring 35 is insufficient to overcome the pressure in the bellows. When the temperature of the air has been depressed to 43°, the bias of the spring 35 is sufficient to overcome the pressure in the bellows 26 and initiates downward movement of the lever 33 so that it is moved out of engagement with the stop 37.

As the spring 41 engages the lever 39, the latter moves downwardly with the lever 33 and out of engagement with the stop 42. When the temperature of the air within the space 11 has been depressed to 42° F., the lever 39 will have been moved sufficiently to effect opening of the switch 44. Accordingly, operation of the compressor and heating of the reservoir 28 are terminated and the reservoir 28 again becomes the controlling factor for determining the pressure within the bellows 26.

As the temperature of the reservoir 28 is relatively low or at a value of 24° F. at this time, the pressure in the bellows is rapidly reduced and the bellows, therefore, contracts until the lever 33 engages the stop 38 which as mentioned hereinbefore occurs when the pressure within the bellows 26 corresponds to temperatures of 29° F. and below. The complete cycle of operation has now been described.

From the foregoing description, it will be apparent that I have provided an improved control for a refrigerator wherein the minimum temperature of the air in the refrigerated zone and the maximum temperature of the evaporator are maintained at predetermined values by a single control mechanism. Accordingly, the evaporator may be operated at sub-freezing temperatures for preserving frozen articles or may be operated so

that its maximum temperature is about 32° F. whereby defrosting during each cycle is effected.

As the minimum air temperature is maintained at a predetermined value, variations of the mean temperature thereof are relatively small during relatively wide variations in the ambient or room temperature. The maximum cabinet air temperature will vary with variations in ambient temperature but the variations in the mean temperature are substantially reduced over a conventional control in which the circulation of refrigerant is under control of the temperature of the evaporator. In the latter case, the mean temperature is subject to wide variation when the ambient temperature varies as the cabinet air exerts substantially no control over the refrigerating machine.

In the present system, the temperature differential of the evaporator will vary with different ambient temperatures although the maximum evaporator temperature is maintained substantially constant. When the ambient temperature is high, the compressor is operated for longer periods in order to depress the cabinet air temperature to 42° F. and, therefore, the minimum evaporator temperature may be depressed to values below 24° F. The minimum evaporator temperature therefore is reduced as the temperature of the ambient or room atmosphere increases. The maximum evaporator temperature is maintained substantially constant for varying ambient temperature but the temperature differential of the evaporator varies inversely with variations in ambient temperature.

In control systems wherein the temperature of the cabinet air controls the refrigerating machine, a substantially constant mean air temperature may be obtained but the temperature of the evaporator will vary so that it may operate above and below a freezing temperature at different times depending upon the temperature of the ambient atmosphere.

It will be apparent that my improved control provides for the selection of various temperatures of the different zones being cooled and that the minimum temperatures of the higher temperature zone may be higher than the maximum temperature of the lower temperature zone. By adjusting the stops 37 and 38, the temperatures at which the switch 44 is opened or closed may be varied, and the mean temperatures of the evaporator and of the cabinet air may, therefore, be varied relative to each other.

While I have shown my invention in but one form, it will be obvious to those skilled in the art that it is not so limited, but is susceptible of various changes and modifications without departing from the spirit thereof and I desire, therefore, that only such limitations shall be placed thereupon as are imposed by the prior art or as are specifically set forth in the appended claims.

What I claim is:

1. In refrigerating apparatus, the combination of means defining relatively low and high temperature zones to be refrigerated, evaporator means for abstracting heat from both zones, means for circulating refrigerant through the evaporator means, a switch for initiating and terminating operation of the circulating means, a thermostatic device for actuating said switch and including first and second elements responsive, respectively, to the temperatures of the low and higher temperature zones, said element responsive to the temperature of the low temperature zone being effective to close the switch 75

during inactive periods of the circulating means, means effective during active periods of the circulating means for transferring control of the switch to the element responsive to the temperature of the higher temperature zone whereby said element is rendered effective to open the switch and means for transmitting movement of the thermostatic device to the switch and providing for overtravel of the device with respect to the switch so that movement is imparted to the switch during the first portion of a movement of the thermostatic device and relative movement between the thermostatic device and the switch is permitted during the remaining portion of the movement of the thermostatic device.

2. In refrigerating apparatus, the combination of means defining relatively low and high temperature zones to be refrigerated, evaporator means for abstracting heat from both zones, means for circulating refrigerant through the evaporator means, a switch for initiating and terminating operation of the circulating means, a bellows for actuating the switch, first and second elements communicating with the bellows and enclosing a volatile fluid, said first and second elements being disposed in heat transfer relation with the media in the low and high temperature zones, respectively, a mechanism for transmitting movement of the bellows to said switch and effective to operate the switch during the first portion of a movement of the bellows and to permit overtravel of the bellows with respect to the switch during the remaining portion of the movement of the bellows, and means effective during operating periods of the circulating means for raising the temperature of the element associated with low temperature zone to a value in excess of the temperature of the element associated with the higher temperature zone.

3. In a refrigerating apparatus, the combination of means defining relatively low and high temperature zones to be refrigerated, evaporator means for abstracting heat from both zones, means for circulating refrigerant through the evaporator means, a switch for initiating and terminating operation of the circulating means, a thermostatic device including a bellows and first and second thermal responsive elements communicating with the bellows and containing an expansible fluid, said first and second elements being disposed in heat transfer relation with the respective low and high temperature zones, a switch for initiating and terminating operation of the refrigerant circulating means, adjustable means for determining the range of movement of the bellows, means for transmitting movement of the bellows to the switch and providing for overtravel of the bellows subsequent to an operation of the switch, said thermal responsive element associated with the low temperature zone being effective during inactive periods of the circulating means for determining the movement of the bellows, and means for rendering the thermal responsive element associated with the high temperature zone effective for controlling the movement of the bellows during active periods of the circulating means.

4. In refrigerating apparatus, the combination of means defining relatively low and high temperature zones to be refrigerated, evaporator means for abstracting heat from both zones, means for circulating refrigerant through the evaporator means, a switch for initiating and terminating operation of the circulating means,

a thermostatic device including a bellows and first and second thermal responsive elements communicating with the bellows and containing a volatile fluid, said first and second elements being disposed in heat transfer relation with the respective low and high temperature zones, said thermal responsive element associated with the low temperature zone determining the pressure in the bellows during inactive periods of the circulating means, means for increasing the temperature of the element associated with the low temperature zone to a value in excess of the temperature of the other thermal responsive element during active periods of the circulating means whereby said other element determines the pressure of the fluid in the bellows, adjustable means for limiting the range of movement of the bellows, a switch for initiating and terminating operation of the circulating means, a movable member for actuating the switch, means for determining the range of movement of the movable member and means for transmitting movement of the bellows to the movable member and providing for overtravel of the bellows with respect to the movable member subsequent to an operation of the switch.

5. In refrigerating apparatus, the combination of means defining first and second zones to be refrigerated at different temperatures, evaporator means for abstracting heat from both zones, means for circulating refrigerant through the evaporator means, control means for initiating and terminating operation of the circulation means, thermal-responsive means for actuating the control means and responsive to a predetermined temperature of the low temperature zone for initiating operation of the circulating means and responsive to a predetermined temperature of the higher temperature zone for terminating operation of the same, said zones being maintained between different high and low temperatures and the low temperature of the high temperature zone being of higher value than the high temperature of the low temperature zone.

6. In refrigerating apparatus, the combination of means defining first and second zones to be refrigerated at different temperatures, evaporator means for abstracting heat from both zones, means for circulating refrigerant through the evaporator means, a switch for energizing and deenergizing the refrigerant circulating means, a movable member actuated in response to the temperature of the low temperature zone during periods when the circulating means is deenergized and actuated in response to the temperature of the high temperature zone during periods when the circulating means is energized, means for limiting the movement of the movable member, a mechanism for imparting movement of the movable member to the switch and including a connection permitting overtravel of the movable member subsequent to an operation of the switch, and means for adjusting the amount of overtravel permitted by said connection.

7. In refrigerating apparatus, the combination of means defining a chamber to be refrigerated, an evaporator for abstracting heat from said chamber, means for circulating refrigerant through the evaporator, a switch for energizing and deenergizing the circulating means, thermally operated means for actuating said switch and responsive to the temperature of the evaporator for closing the switch and to the temperature of the media in said chamber for opening the same, a lost motion mechanism for imparting move-

ment of the thermally operated means to the switch and providing for overtravel of the mechanism subsequent to an operation of the switch and means for adjusting the amount of overtravel of the mechanism whereby the temperatures at which the switch is opened or closed may be varied.

8. In refrigerating apparatus, the combination of means defining a chamber to be refrigerated, an evaporator for abstracting heat from said chamber, means for circulating refrigerant through the evaporator, a switch for energizing and deenergizing the circulating means, an expansible bellows for having thermal elements communicating therewith and disposed respectively in heat transfer relation with the evaporator and the media cooled thereby, said elements and bellows enclosing an expansible fluid, a lever for actuating said switch, means defining a connection between said bellows and said lever and providing for overtravel of the bellows with respect to the lever, means for adjusting the amount of said overtravel whereby the temperature at which the switch is opened or closed may be raised, and means for transferring control from one of said thermal elements to another so that the element associated with the evaporator is effective during inactive periods of the circulating means and the element associated with the media being cooled is effective during active periods thereof.

9. In refrigerating apparatus, the combination of means defining a chamber to be refrigerated, an evaporator for abstracting heat from said chamber, means for circulating refrigerant through the evaporator, a switch for energizing and deenergizing the circulating means, an expansible bellows for having thermal elements communicating therewith and disposed respec-

tively in heat transfer relation with the evaporator and the media cooled thereby, said elements and bellows enclosing an expansible fluid, means for selectively rendering the thermal elements effective to control expansion of the bellows so that the element associated with the evaporator is active during deenergized periods of the circulating means and the element associated with the media cooled by the evaporator is effective during energized periods of the circulating means, means for limiting the amplitudes of the bellows, a lever for actuating the switch, means for limiting the movement of the lever and defining a range of movement therefor and a frictional connection between the bellows and said lever whereby movement of the bellows is imparted to the lever when the latter is intermediate the limits of its range of movement and movement of the bellows relative to the lever is permitted when said lever is at one of the limits of its range.

10. In refrigerating apparatus, the combination of means defining a zone to be cooled, an evaporator for abstracting heat from the media in said zone, means for circulating refrigerant through the evaporator, means for controlling the operation of the circulating means and movable to first and second positions wherein the circulating means is active and inactive, respectively, means for actuating the controlling means and including elements responsive, respectively, to the temperature of the evaporator and the media cooled thereby, means for selecting the element which is to actuate the controlling means and means defining a lost motion connection between the actuating means and the controlling means and providing for overtravel of the actuating means with respect to the controlling means.

LESLIE B. M. BUCHANAN.
